CLAIM

(52) **U.S. Cl.** **D14/491**

(57)

The ornamental design for a display screen or portion thereof with a group of graphical user interfaces, as shown and described.

(58) **Field of Classification Search**

DESCRIPTION

USPC ..... D14/485—495; 345/1.1, 1.2, 2.1—2.3, 3.1,
345/902; 715/763, 810, 836, 837, 846,
715/847, 977

The FIGURE is a front view of a display screen or portion thereof with a group of graphical user interfaces showing the claimed design.

CPC G06F 3/048; G06F 3/0481; G06F 3/0482;
G06F 3/04817; G06F 3/0482; G06F
3/0483; G06F 3/0484; G06F 3/04847;
G06F 3/0485; G06F 3/04855; G06F
3/04886; G06Q 30/00; H03J 1/00; H03J
1/0008; H03J 1/0016; H03J 1/0025;
H04N 5/00; H04N 5/08; H04N 5/14;
H04N 5/222; H04N 5/225; H04N 5/232;
H04N 5/445; H04N 5/4453; H04N 5/45;
H04N 2005/44517; H04N 2005/44521;

The bracket shown in the FIGURE indicates a group. The elements of the group are arranged relatively on the drawing sheet for the convenience of illustration, and the placement of each element relative to another, or to the drawing sheet, forms no part of the claimed design.

1 Claim, 1 Drawing Sheet

APPLICATION NO. : 29/665852
DATED : June 30, 2020
INVENTOR(S) : Butcher et al.

Page 1 of 1

It is certified that error appears in the above-identified patent and that said Letters Patent is hereby corrected as shown below:

On the Title Page

In the Inventors item (72), delete:
“Joseph Chan, San Francisco, CA (US);”

In the Description item (57), add the following paragraph between the first and second printed paragraphs:

--The broken lines in the Figure show a display screen or portion thereof, and form no part of the claimed design.--

Signed and Sealed this
Eleventh Day of August, 2020

Andrei Iancu
Director of the United States Patent and Trademark Office
